United States Patent Office.

WILLIAM B. COATES, OF PHILADELPHIA, PENNSYLVANIA, ASSIGNOR TO EDWIN CLINTON AND W. HARRISON EISENBREY, OF SAME PLACE, FOR THREE-FOURTHS OF THE INVENTION.

Letters Patent No. 91,089, dated June 8. 1869.

IMPROVED HAIR-DYEING BRUSH.

The Schedule referred to in these Letters Patent and making part of the same.

To all whom it may concern:

Be it known that I, WILLIAM B. COATES, of Philadelphia, in the State of Pennsylvania, have invented a new "Self-Supplying Hair-Dyeing Brush;" and I do hereby declare that the following is a full and exact description thereof, reference being had to the accompanying drawings, and to the letters of reference marked thereon, making a part of this specification.

The nature of my invention consists in constructing a "self-supplying hair-dyeing brush" upon a new principle of operation, whereby it is not depending upon the existence of any gum or cork-valve between the bottom of the bottle and the bristle-plate, as the dye is retained in the bottle by the exclusion of air from the neck, (by closing the air-hole in the cap,) and by a screw pressure downwards on the centre of bristle-plate.

To enable others skilled in the art to make and use my invention, I will proceed to describe its construction and operation.

On reference to the drawings—

Figure 1, a perspective view of the brush.

Figure 2, a top view of the body of the brush without the bottle, showing the bottom inside.

Figure 3, a longitudinal section of brush.

Figure 5, a perspective view of the gum bag.

The body of the brush A can be constructed of wood, bone, ivory, glass, gutta-percha, or metal, and can be of any size or in any style desired to please the fancy.

In the top there is a circular opening, extending vertically nearly through to the base, leaving only sufficient thickness for the draw-holes a to insert the bristles D, and provided with a screw-thread, b, around the inside, for screwing in the dye-receptacle C.

In the bottom are several dye-discharge holes c, arranged between the first and second circles of bristles, though they can be placed between any of the circles if desired.

The gum (or cork) circle E, cut to suit the diameter of the vertical opening in the body of the brush, has discharge-holes c', to coincide with those in the bottom of the vertical opening, but has no hole in the centre.

The handle B is small and neat, and can be screwed, glued in, or cast on solid in a mould with the body.

The dye-receptacle C should be larger at the upper than at the lower portion, forming a small shoulder, which rests upon the top of A when the screw around the lower part is screwed into the vertical opening of the brush-body. The upper portion of C is a trifle smaller than A, so as to set inside of the edge of the latter, and has a dye-discharge hole in the centre at the bottom.

On the top is a neck, with a screw around it, to screw on the metal cap F.

The cap has an inside piece of gum or cork, and a small air-hole, e, on the side, just below the inside gum or cork.

The gum bag G is made only large enough to contain the brush, and has a draw-cord to secure the neck.

The dye-receptacle or bottle is screwed down on the flat surface or smooth portion of the bristle-plate, and the bottom of the bottle being perfectly even, fits so tightly as to prevent any escape of dye.

I am enabled to accomplish my object through the medium of a correct scientific principle applied to the cap on the neck of the bottle.

This principle is, that where a small hole exists in the bottom of a bottle, and the bottle is filled with paint, the pressure of the air upwards keeps it in, and it would not run out unless air should be admitted at the top, and, water even will not drop out without admission of air.

Now, my bottle, if taken out and held up after being filled with die, would not drop any from the hole in the bottom until the air-hole e, in the cap F, on the neck of the bottle, should be opened.

The operation of my brush is as follows:

Take hold of the body with the thumb and forefinger of the left hand; then with the right-hand thumb and forefinger loosen the cap on the neck of the bottle, so that the air-hole e in the side of the cap may be open; then take hold of the body of the bottle and turn quickly from the right towards the left, when the dye will be forced or dashed out into the bristles, and not merely run or drop on them. When the brush is ready take hold of the handle. By placing the bristles on a few thicknesses of paper, the dye will not soil the hands. After using the brush, wipe off the bristles and tie it up in the bag.

My brush can be made very cheaply and easily, and will not get out of order like those having valves to wear away by friction.

I make no claim to a mere fountain-brush alone, or a brush having a reservoir for holding a liquid and a valve to regulate its flow on the bristles.

What I claim as my invention, and desire to secure by Letters Patent, is—

The combination of the brush A with the bottle C, all constructed and arranged as and for the purpose specified.
